UNITED STATES PATENT OFFICE.

CHARLES D. SOURS, OF MARTINSVILLE, VIRGINIA, ASSIGNOR OF ONE-HALF
TO NAT. R. MORRIS AND JAMES H. SPENCER, BOTH OF SAME PLACE.

PLUG-TOBACCO SHAPER.

SPECIFICATION forming part of Letters Patent No. 486,302, dated November 15, 1892.

Application filed July 9, 1890. Serial No. 358,178. (No model.)

To all whom it may concern:

Be it known that I, CHARLES D. SOURS, a citizen of the United States, residing at Martinsville, in the county of Henry and State of Virginia, have invented new and useful Improvements in Plug-Tobacco Shapers, of which the following is a specification.

In plug-tobacco shapers a mold-frame having cells corresponding in form to the shape of the plugs desired is placed on a plane-surfaced backing or base-plate, and into the cells at a point opposite the base-plate are inserted the sinkers, secured to the usual sinker-plate for pressing the tobacco contained in the cells into plugs between the base-plate and the inner ends of the sinkers—as, for example, in Letters Patent No. 73,354, issued January 4, 1868. In this type of plug-shapers some of the tobacco will be pressed out between the adjacent surface of the base-plate and the lower end walls of the cells, in consequence of which it is essential to trim the plugs after they are shaped, which results in a serious loss of tobacco, in addition to which the time and labor required for trimming is expensive, while the plugs are not all produced of uniform size and exactly true at the edges.

In the manufacture of plug-tobacco in the manner described it is desirable to employ a set of twelve (more or less) mold-frames and their concomitants, which are placed in the press to simultaneously shape and produce a large number of plugs; but in the prior construction if the mold-frames are arranged in a set some of the tobacco passes out at the lower edges of all the cells, as before stated, and for this reason the prior construction is very objectionable.

The present invention has for its object to avoid the objections mentioned; to provide a novel sinker-frame having sinkers on both surfaces, those on one surface being thicker than those on the opposite surface, whereby the sinkers project into the cells of the mold-frames for producing plugs exact and true in shape and size; to provide novel means whereby a sinker-plate for pressing tobacco in one mold-frame also subserves the function of preventing the passage of tobacco from the lower ends of the cells in a mold-frame placed above and resting thereupon, and, finally, to

improve the construction of plug-tobacco shapers, whereby the tobacco is prevented from being pressed out at the ends of the cells, the loss of tobacco is avoided, more accurate work is produced with less labor and expense, racking or sliding of the mold-frames is avoided, and plugs are produced of uniform size and shape. To accomplish all these objects, my invention involves the features of construction and the combination or arrangement of devices hereinafter described and claimed, reference being made to the accompanying drawings, in which—

Figure 1 is a perspective view of an upper sinker-frame constructed in accordance with my invention. Fig. 2 is a perspective view of one of the mold-frames with its cells. Fig. 3 is a perspective view of a lower sinker-frame. Fig. 4 is a transverse sectional view of a series of the sinker-frames and mold-frame arranged in proper relation to form tobacco-plugs, and Fig. 5 is a longitudinal sectional view of the same.

In order to enable those skilled in the art to make and use my invention, I will now describe the same in detail, referring to the drawings, wherein—

The numeral 1 indicates a cell mold-frame constructed of longitudinal and transverse strips 2 and 3, so connected and organized as to provide a series of cells 4 of uniform shape and size. The sinker-frame is composed of a rectangular plate 5, having at each longitudinal edge a rectilinear bar 6, extended at each end into a handle 7, which flanges or bars serve to receive between them one of the mold-frames, while the handles serve to manipulate the sinker-frames.

The sinker-frame is provided with a series of projecting sinkers 8 on one surface and on the opposite surface with a series of projecting sinkers 9. The sinkers on each surface are arranged at a suitable distance apart, the intervening space corresponding in width to the thickness of the strips or bars comprising the mold-frame, and the sinkers 9 on one surface are thicker or of greater depth than the sinkers 8 on the opposite surface for the purpose of producing plugs uniform in size and for rendering it possible to reduce the depth of the mold-frames, and thereby lessen the

height of a stack of the sinker and mold frames. Those on the opposite surface, in other words the sinkers 8, are of greatly-reduced thickness as compared with the sinkers 9. The thinnest sinkers 8 correspond in number with the thickest sinkers 9, and all the sinkers on each sinker-frame are coextensive in length and breadth in order to accurately fit the cells of two adjacent mold-frames, and in practice the sinkers 9 enter the cells of a lower mold-frame and the sinkers 8 enter the cells of an upper mold-frame, the superimposed arrangement of mold-frames and sinker-frames being clearly shown in Figs. 4 and 5.

The tobacco to be shaped into plugs occupies the cells between the adjacent faces of the sinkers on an upper and a lower sinker-frame, and when a set of the mold-frames is placed in the press to effect the pressing operation the thinnest sinkers accurately fill up the lower ends of the cells and effectually prevent any tobacco from being pressed out at such points, while the thickest sinkers follow up the tobacco in the cells of the mold-frames until the tobacco is properly compacted into the form of plugs desired.

In the construction described and shown the upper and lower edges of the cells in the mold-frame are locked against movement by abutment against the edges of the sinkers on the sinker-frames, while the longitudinal strips 3 of the mold-frames are located between and bear against the rectilinear side bars 6 of the sinker-frames, whereby racking of all the frames is prevented, or, in other words, the mold-frames and sinker-frames cannot slide one upon the other, but are all held in correct relation throughout the series.

I have exhibited each sinker-frame as formed integral with its thin and thick sinkers; but I do not confine myself to this particular construction.

By my invention I avoid the necessity of trimming the plugs after the sinker operation and produce nice and accurate work with comparatively-little labor and expense, while the engagement of the sinker-frames and mold-frames with each other, to avoid racking,

renders such frames durable and efficient in practice. The construction also prevents the mold-frames and the pressing-frames from being set up untruly and causes the plugs to be prized up in the center of the cells and not at the edges thereof. The sinker-frames and the mold-frames may be arranged in a set of twelve, more or less, and thus a large number of tobacco-plugs can be simultaneously produced without loss of tobacco or subsequent trimming of the plugs.

What I claim is—

1. The combination, in a plug-tobacco-shaping apparatus, of sinker-frames each having on both surfaces a series of sinkers, those on one surface being thicker than those on the opposite surface and each series of sinkers separated from each other to provide longitudinal and transverse spaces, with the cell-mold frames composed of longitudinal and transverse strips and interposed alternately between the sinker-frames, so that the sinkers on one surface of a sinker-frame project into the cells of one mold-frame while the sinkers on the opposite surface project into the cells of another mold-frame, substantially as described.

2. The combination, in a plug-tobacco-shaping apparatus, of sinker-frames each having upwardly-projecting side bars and provided on both surfaces with a series of sinkers, those on one surface being thicker than those on the opposite surface and each series of sinkers separated from each other to provide intervening longitudinal and transverse spaces, with the cell mold-frames composed of longitudinal and transverse strips and interposed alternately between the sinker-frames, said cell mold-frames having their outer longitudinal strips located between and bearing against the upwardly-projecting side bars on the sinker-frames, substantially as described.

In testimony whereof I have affixed my signature in presence of two witnesses.

CHARLES D. SOURS.
